Attorney

UNITED STATES PATENT OFFICE.

HANS SCHMIDT, OF CHARLESTON, WASHINGTON.

EMBROIDERY FRAME.

Application filed March 27, 1926. Serial No. 97,988.

This invention relates to embroidery frames involving inner and outer concentric hoops, the material being drawn over the inner hoop and clamped by the outer hoop.

5 The main object of the present invention is the provision of means whereby the outer hoop may be readily operated to insure clamping cooperation with the inner hoop or wholly separated from such clamping cooperation at will, whereby to materially facilitate the application of goods to the inner hoop and its removal therefrom.

A further object is the provision of means by which the inner hoop is removably supported in a comparatively rigid manner to facilitate the application of the goods and outer hoop and avoid the necessity of the operator supporting the hoops while embroidering.

10 The invention is illustrated in the accompanying drawings, in which:

Fig. 1 is a plan view showing the hoops in clamping relation.

Fig. 2 is a broken plan showing the hoops in non-clamping relation.

Fig. 3 is an elevation illustrating particularly the support for the inner hoop.

Fig. 4 is a sectional view showing the clamping cooperation of the hoops.

15 The invention comprises an inner hoop 1, which as usual, is an integral circular member, over which the fabric is to be drawn and clamped for the usual and well understood embroidery operation. The outer hoop

2 is similar in shape and sectional area to the inner hoop, but is divided or split at 3. An ear 4 projects from the outer side of the hoop 2 near the point of division and supports levers 5, the opposite ends of which are connected to a finger lever 6, pivotally supported at 7 on an ear 8 secured to the hoop 3 at the opposite side of the split. The finger lever 6 is eccentrically mounted on the ear 8 so that in one position, that is, down

20 in contact with the surface of the hoop, the levers 5 are drawn upon to force the divided ends of the hoop together, the opposite position of the finger lever of course forcing the ends of the hoop 2 apart.

If desired, and as preferred, the ends of 50 the hoop 2 adjacent the division may be guided in U-shaped guides 9 secured to one or the other of the ends of the hoop.

A support is provided for the inner hoop 2, comprising an upright 10 having a clamp 11 at the lower end, by which the upright may be fixed to any convenient edge structure. The upper end of the upright 10 is divided to form spaced projections 12 and 13, the former being provided with a set 55 screw 14. The inner surface of the hoop 1 is provided at an appropriate point with a bracket 15 cutaway intermediate its ends to provide an inner recess 16 and an outer recess 17, the latter being between the bracket and hoop. The respective projections 12 and 13 fit into the recesses 16 and 17 and when the set screw is tightened, the inner hoop is fixedly supported at right angles to the upright 10 in a position convenient to the operator with the goods wholly free of obstruction.

60 As will be apparent from the drawings, the goods to be embroidered are stretched over the hoop 1, following which the hoop 2 in open relation is passed down over the goods outwardly of the hoop 1. The finger lever 10 is then operated to draw the ends of the hoop 2 together, thus clamping the goods between the hoops 2 and 1 in the obvious 65 manner.

70 What I claim is:—

A support for the inner hoop of cooperating embroidery hoops, a bracket secured to the inner surface of the inner hoop, said bracket having parallel vertical recesses on opposite faces, an upright having a divided end to form two vertical legs, which fits within the vertical recesses in the bracket, a fastening screw extending through the innermost leg of the upright, and engaging the bracket to removably secure the bracket and inner hoop together, and means carried by the loose end of the upright to engage a feature whereby the outer surfaces of the inner 75 hoop is wholly free of any obstruction.

80 In testimony whereof I affix my signature.

HANS SCHMIDT.
